United States Patent Office

Des. 203,231
Patented Dec. 14, 1965

203,231

DISPLAY BOX

Albert Merrill Cohen, 3418 Edcrest Road,
Baltimore, Md.

Filed Jan. 22, 1965, Ser. No. 83,573

Term of patent 7 years

(Cl. D58—12.6)

FIG. 1.

FIG. 2.

FIG. 3.

FIG. 4.

I claim:

The ornamental design for a display box, as shown.
